UNITED STATES PATENT OFFICE.

JEROME FRANCIS O'CONNOR, OF NEW YORK, N. Y.

DESIGN FOR A BOTTLE.

47,565.

Specification for Design.

Patented July 13, 1915.

Application filed April 2, 1915. Serial No. 18,828. Term of patent 3½ years.

To all whom it may concern:

Be it known that I, JEROME FRANCIS O'CONNOR, a citizen of the United States, residing in the city of New York, borough of Brooklyn, in the county of Kings and State of New York, have invented a new, original, and ornamental Design for a Bottle, of which the following is a specification, reference being had to the accompanying drawing, forming part thereof.

The figure is a side elevation of a bottle showing my new design.

I claim:

The ornamental design for a bottle, as shown.

JEROME FRANCIS O'CONNOR.

Witnesses:

ESTELLA M. WALTON,
ESTHER H. ZIERING.
